UNITED STATES PATENT OFFICE

EWALD ERNEST STURK, OF HOLLYWOOD, CALIFORNIA

CAP AND TUBE FOR TOOTH PASTE AND THE LIKE

Application filed April 14, 1928. Serial No. 269,896.

This invention relates to closures for collapsible tubes for tooth paste and the like, and has for one of its objects to provide a novel, simple and inexpensive device of this 5 character which cannot be removed from the tube and become lost, which may be easily and quickly moved into opened or closed position, which will when in closed position prevent the entrance of air into the tube, and 10 which when in opened position will permit the tooth paste or the like to be expelled from the tube easily and in a convenient manner.

With the foregoing and other objects in 15 view, the nature of which will appear as the description proceeds, the invention consists in the novel construction, combination and arrangement of parts hereinafter fully described and claimed, and illustrated in the 20 accompanying drawing, wherein:

Figure 1 is a view in side elevation of a collapsible tube equipped with a closure constructed in accordance with my invention,

Figure 2 is a top plan view of the tube 25 and closure,

Figure 3 is a sectional view taken on the vertical plane indicated by the line 3—3 of Figure 1,

Figure 4 is a top plan view of the tube 30 with the closure removed,

Figure 5 is a detail perspective view of the closure, a portion of the closure being in vertical section, and

Figure 6 is a view similar to Figure 3 illustrating a slightly modified form of the invention.

Referring in detail to the drawing, 1 designates the body, 2 the neck and 3 the closure of the tube.

40 The closure 3 is in the form of a conical cap, and the upper end portion of the neck 2 is of conical formation to provide a seat 4 for the cap. The neck 2 is provided at the base of the seat 4 with an outer annular rib 5. The neck 2 may be solid, as shown in Figures 1 to 5, or hollow, as shown in Figure 6. When of solid construction, the neck 2 is provided with an angular discharge passage 6 which opens out through the side of the 45 seat 4. When the neck is of hollow construc-

tion, the seat 4 is provided with a discharge port 7.

The cap 3 is rotatably arranged on the seat 4, and it is held in place by an annular flange 8 which extends downwardly from its base and surrounds the rib 5 and which has its lower portion cut as at 9, and bent into contact with the under side of the rib. The cap 3 is provided in its side with an opening 10 which when the cap is in opened position registers with the discharge end of the passage 6 or with the port 7 depending upon whether the neck 2 of the tube is hollow or solid. When the cap 3 is in closed position the opening 10 is out of registration with the passage 6 or port 7. To permit it to be easily moved from one of its positions to the other, the cap 3 is provided at its base with a milled annular rib 11 adapted to be engaged between the fingers. To limit the movement of the cap in opposite directions and thus insure its being moved into its fully closed or fully opened position, means, consisting of a rib 12 carried by the cap and a short groove 13 formed in the seat 4 for the 75 reception of the rib, are provided.

The formation of the cap 3 and the seat 4 permit these parts to contact in a manner to prevent the entrance of air into the tube and the formation of these parts and the location of the discharge opening 10 within the side of the cap to permit the tooth paste to be applied to a brush in the most convenient manner and permit the closing of the cap and the application of the paste to the 80 tooth brush without waste.

Changes in details may be made without departing from the spirit or the scope of the invention as claimed.

What I claim as new is:

A collapsible tube embodying a conical head having an opening in its side communicating with the interior of the tube and with a circumferentially extending groove in the head spaced from the opening, a neck underlying and of less diameter than the head and separated therefrom by a cylindrical part, said cone, neck, and cylindrical part being coaxial, a cap fitting upon the cone and having a port properly positioned to register 100

with the opening, a cylindrical part having
a knurled band as an exterior and fitting
upon the cylindrical head, a flange extending
below the cylindrical part and bent inwardly
toward the neck, and an inwardly upset part
5 of the cap engaging in the groove and limit-
ing rotary movement of the cap to proper
registration.

In testimony whereof I affix my signature.
